MACHINE FOR FINISHING TOP-LIFT EDGES

Oscar L. Lawson, Lynn, Mass., assignor to Lawson-
Porter Shoe Machinery Corp., Lynn, Mass., a
corporation of Massachusetts

Application March 16, 1938, Serial No. 196,294

28 Claims. (Cl. 12—74)

My present invention is a novel and improved apparatus or machine for operation on the top lift edges of heels, and comprises a novel method for edge-finishing or edge-setting of the entire periphery of the top lift, both along the heel breast and around the rest of the edge.

Heretofore, it has been customary to either complete the edge-fitting or setting operations by a hand-burnishing tool or by a machine tool against which the heel and attached top lift were held and oscillated, in which case the heel breast still had to be set by hand. In such prior operations, the top lift, usually attached to a wooden heel, was mounted on an oscillated jack and the heel moved in contact with the fixed edge-setting tool while the jack and the attached heel was rotated or oscillated.

Such prior devices, wherein the jack and heel as well as the top lift were movable, providing for rotative movement against the entire heel-clamping devices, rendered the machine extremely complex; and furthermore, no prior method, so far as I am informed, has ever been devised to finish and set the edge entirely around the periphery of the top lift, viz., across the heel breast, as well as around the sides and back.

My present invention is directed to overcome the difficulties heretofore experienced in machines of this type and, furthermore, to provide novel, improved, and automatic means to effect a complete edge-fitting and setting operation entirely around the periphery of the top lift, both across the heel breast, around the sides and back, and even on the corners of the top lift.

A further important feature consists in my means and mechanism for producing this complete edge-finishing operation, substantially simultaneously, or substantially successively, and with a plurality of edge-setting tools.

Further important features consist in the arrangement of yielding mechanism to hold the operating tools in contact with the top lift while the heel and top lift are held relatively rigid, and the edge-setting tools are oscillated about the same.

A still further feature consists in the capacity of angular adjustment of the edge-setting tool relatively with the heel and top lift to be operated upon, since top lifts are frequently formed with a bevel or other divergent angle relatively to the base of the wooden heel to which they are attached and, hence, the finishing, burnishing, or setting tool must accurately fit such angle, and I have provided efficient means to effect this adjustment.

Still further features consist in the capability of providing a heating element carried by the oscillating tool and supplying heating means to such element during the oscillation of the tool.

Still further novel features consist in the means

of automatic adjustment and for clamping of the heel and its attached top lift in the machine, means for performing the prescribed plurality of burnishing operations or oscillations, and thereupon releasing the heel-clamping mechanism to permit the operator to remove the finished heel and replace it with another to be operated upon.

An additional and important feature consists in means for adjusting the tension of the setting tools on the work, as well as adjusting the angle of the same, and also permitting these adjustments to be made without stopping the machine and during its continuous operation.

In carrying out my invention I provide a simple, economical, efficient, and compact apparatus operating on the novel method of holding the heel relatively fixed while oscillating the edge-setting tools thereabout, and I believe this is a distinct novelty in this art and, therefore, I wish to claim the same herein broadly.

Referring to the drawings illustrating a preferred embodiment of my present apparatus, to carry out my novel method of edge-finishing;

Fig. 1 is a side view of my machine;

Fig. 2 is a plan view;

Fig. 3 is an enlarged fragmentary view of one type of finished top lift;

Fig. 4 is an enlarged cross-sectional fragmentary view showing the edge-setting tools operated on the heel breast and the rear of the top lift simultaneously and showing the work-rest against which the top lift is positioned;

Fig. 5 is an end view looking from the left of Figs. 1 and 2;

Fig. 6 is a cross-sectional view on the line 6—6 of Fig. 1 illustrating the normal position of the devices to lift the burnishing tool;

Fig. 7 is a corresponding view to Fig. 6 showing a different position of the locking latch;

Fig. 8 is a fragmentary view illustrating the further operation of the latch in Figs. 6 and 7;

Fig. 9 is an end view from the right of Figs. 1 and 2;

Figs. 10 and 11 are cross-sectional views, respectively, on the line 10—10 of Fig. 1, showing the edge-setting tools in retracted and then inoperative position relatively with the top lift;

Fig. 12 is a cross-sectional fragmentary view illustrating the edge-setting tools at the limit of their respective paths of oscillation;

Fig. 13 is a cross-sectional view on the line 13—13 of Fig. 9;

Fig. 14 is an enlarged cross-sectional view on the line 14—14 of Fig. 13;

Fig. 15 is a cross-sectional view on the line 15—15 of Fig. 13;

Fig. 16 is a fragmentary cross-sectional view on an enlarged scale on the line 16—16 of Fig. 13;

Fig. 17 is a fragmentary view on the line 17—17

of Fig. 14 showing the means for adjustment of the spring tension.

Fig. 18 is a fragmentary cross-sectional view of the spring and adjusting means cooperating with the cam section on the heel breast edge-setting tool.

Figs. 19 and 20 are fragmentary views illustrating the different operative positions of certain cam and latch mechanism.

Referring to the drawings, 1 designates a suitable support, to which a base plate 2 is attached by bolts 3-3, said base plate having formed thereon upstanding side frames 5 and 6 and a rear cross-frame 7 which carry the various bearings and supporting means for the apparatus. Formed in the upstanding frame 6 is a bearing 8 to receive the shaft 10 of a drive pulley 12, which pulley is mounted on a hub 13 on said shaft 10 outside the bearing 8 and is rotated by a belt 14 connected with any suitable source of power. On the inner end of the shaft 10 is secured a pinion 15, viewing Figs. 1 and 2, meshing with and driving a gear 16, which gear is mounted on a hub 17 and is freely rotatable on a clutch shaft 18, rotatable in suitable bearings 20 on the frame 5, and 21 on the frame 6.

As the belt 14 and pulley 12 are in constant rotation, as well as the pinion 15 and the gear wheel 16, in order to connect the same with the clutch shaft 18 and operate the mechanism, I provide a sliding clutch 25 carried by a hub 26 keyed to the shaft 18 and operable toward a cone clutch-bearing 27 secured to the face of the gear wheel 16 by the action of a coiled spring 28 surrounding said clutch shaft 18. The hub 26 is formed with a groove in which a shifting lever 30 operates and is pivoted at 31 on a bracket 32 secured to the base 2 by bolts 34 passing thru a flange 33 formed on the bracket 32, as best shown in Figs. 1 and 11.

The lower end of the shifting lever 30 is provided with an adjustably threaded bearing screw 35, adapted to be engaged by a flattened face 36 formed on a shaft 37 with cut-away corners 39-39 between each side of the face 36, said shaft being mounted in a lug upstanding from the flange 33 and having a lever 40 secured to said shaft 37 to operate the same. Swinging of the lever 40 acts to oscillate the shifting lever 30 on its pivot 31 and to either compress the spring 28 and release the clutch shaft 18 from engagement with the gear 16 or to permit the spring to force the clutch members 25 and 27 into engagement and, hence, to connect the clutch shaft 18 with the rotating gear 16, as will be readily understood.

I have devised important apparatus to perform a predetermined number or series of oscillating actions on the edge-finishing tools and, thereupon, to withdraw said tools and simultaneously to release the clamping action holding the heel in its position. This momentary heel-releasing movement permits the operator to remove a finished heel and to replace the same with another heel to be operated on, just sufficient time being allowed for this operation. Thereupon, the clamping devices are actuated to engage and hold the new heel, to force it in position against a work-rest, and immediately thereafter for the burnishing tools on the rear and on the heel-rest to be moved into contact with the top-lift, and the series of edge-setting, burnishing, and finishing operations to be performed and then the releasing actions to occur, all in a complete

automatic cycle and without stopping the mechanism.

Also, I have arranged the heel-clamping members, as well as the burnishing tools, in a way to insure that the operator may have a minimum of effort in placing, removing, and replacing with another heel, as well as to insure as a safety factor the operator's handling of the heel. In fact, it is perfectly feasible for the operator to keep 5 a hand on the heel being operated on during the entire oscillations of the burnishing tools as well as during the clamping and releasing actions of the heel-engaging members. This advantage is secured by having the heel blank in a horizontal 10 position and against a bottom rest bearing on the heel breast of the shoe and keeping the heel stationary in relatively fixed position while the edge-setting tools are oscillating around the top lift.

15 The heel-clamping devices will now be described. Formed on the upper part of the frame 5 (see Figs. 1 and 13) is a hub 42 thru which a shaft 43 may slide. Also formed as a laterally extending flange on the top of the frame 5 is a bracket 45 carrying a hub 46 thru which a sleeve 47 slides, said sleeve carrying on its interior a shaft 48 in alignment with the heel 50 to be operated on, and having a rocking plate 51 provided with a pair of ears 52 mounted on a pivot 30 53 thru the end of the shaft 48. This rocking plate 51 has a mass of rubber or fibrous material 35 adapted to yieldingly engage the heel-seat portion of the heel 50 when the shaft 48 is moved in contact with the heel 50, said rubber 55 extending thru a central opening in a plate 56 adapted to engage the marginal edge of the heel.

This plate 56 is also yieldingly mounted and secured to the rocking plate 51 by a plurality of headed screws 57 with their respective shanks 40 passing thru recesses in the rocking plate 51, and with the other end adapted in a plate 58 and each with a coiled spring 59 bearing there-between, see Fig. 13.

The shaft 48 within the sleeve 47 has a considerable portion formed with the reduced diameter to permit a coiled spring 60 to encircle the reduced diameter, as shown at 61, of the shaft 48, which coil bears between a plug 62 at the end of the sleeve 47, viz. at the right viewed 50 in Figs. 1 and 13, and the shoulder formed between the main diameter of the shaft 48 and the reduced portion 61. This reduced portion 61 extends beyond the plug 62 and is rigidly attached to a link 66 by a pair of nuts 64 and 65 being threaded around the end 61. This link 55 extends downwardly and is formed with a split portion at 67 to engage and be clamped about a bar 68 by a clamp 70 passing thru the split arms 67, which bar 68, in turn, is pivoted at 71 to a 60 forked end of the shaft 43, which is adapted to slide in the bearing 42. Said shaft 43 at its forward end is also forked, as shown at 73, to receive a work-rest 75 which can be raised and lowered in the forked portion 73 and held in adjusted position by tightening a set screw 74. On the top of the work-rest is secured a heel-engaging member of rubber, fibre, or other suitable material 77 by a screw 76 which is adjusted for proper height on which to rest the heel breast of the heel 50.

The shafts 43 and 48 are capable of being moved parallel in their respective bearings 42 and 46 and, being attached by links 66, thus enables the heel 50 to be placed in position on the rest 77 and loosely in contact with the rub-

ber 55 on the tilting plate 51 while the shafts 43 and 48 are in retracted position, viz., moved at the right viewed in Figs. 1 and 2. Thereupon, a sliding movement of the shafts will permit the bottom of the top-lift 80 to engage a work-rest 81 (Fig. 15), preferably of relatively hard yielding material such as Uskide, fitted in a cup-shaped member 82 mounted on a rod 84 rigidly adjusted to the desired position and in alignment with the burnishing tools and between which clamping members 81 and 55 the heel 50 is held during the operation of the edge-setting tools.

This rod 84 is adjustable lengthwise by manipulation of a rotatable thumb nut 85 threaded on the rear portion of the rod and bearing against the upstanding portion 86 of a bracket 87 secured to the frame 6. The forward part of the shaft 84 adjacent the cup 82 is adapted to slide in a bored opening thru a center hub-like portion 88 of the face plate 90 on the oscillating tool-holding member, to be described.

In order to effect longitudinal movement of the rod 84 to adjust the same by rotation of the thumb nut 85 I hold said shaft against rotative movement by forming a groove 92 at the outer end, viz., at the left viewed in Figs. 1 and 3, and fit a set screw 91 thru a bored opening in the portion of the bracket 86 to engage the groove 92.

The mechanism for holding and operating the burnishing tools 100 and 101 will now be described.

I provide the burnishing, edge-setting, and finishing tool 100 of suitable contour with the depending flange to fit over and contact with the sides and rear of the top-lift 80, oscillating the same under spring tension, and preferably under an adjustable spring tension, to effect the finishing operation on the main periphery of the top-lift. The finishing tool 101 is arranged to oscillate to-and-fro over the heel breast portion of the top-lift and both tools are simultaneously withdrawn from contact with the top-lift in the cycle of operations when the heel-clamping instrumentalities are released to permit the change of removing a finished heel and one to be operated on.

It is desirable to have the tool 100 interchangeable to fit different widths and forms of top-lifts, and for this purpose the tool 100 is provided with a recess or opening to fit over a stud 102 which is secured in the sliding head 103, a spring 104, which is attached to the head by a screw 105, acting to hold the tool 100 in position and swinging the spring 104 at either side, upon loosening the screw 105, permitting the replacement of the tool 100, see Figs. 4 and 13.

Also fitted in the head 103 is an electrical heating unit 106, which preferably extends into direct contact with the portion of the tool 100, said tool being recessed to receive the same, as best shown in Fig. 4 at 107. This head 103 is arranged to slide in the arc of a circle with the bottom edge of the top lift as the center. To accomplish this purpose I form on the head 103 an undercut guide 110 fitting in a corresponding slideway 112 formed in the block 115, both guideway and slideway being in the form of an arc to permit the adjustment of the tool 100 about the lower edge of the top lift, as above noted.

A flat spring 116 secured by a screw 117 in the block 115, and having an end portion 118 in contact with the rear extension of the head 103 (see Fig. 13) will serve to frictionally hold the

head 103 to whatever position it may be adjusted in the guideway and, hence, relatively with the block 115. The parts just described are constructed and arranged to extend thru an opening 120 in the face plate 90 and the block 115 is mounted upon, or is integral with, a post 121 vertically positioned immediately back of the face plate 90 and has its lowermost portion secured to a reduced part 122 of the shaft 123. Said shaft has its end, viewing the right of Fig. 13, swaged or fitted in a slide 125, mounted for vertically sliding movement in a guideway 126 on the rear of the face plate 90.

At the opposite end of the shaft 123 (see Figs. 6, 7, 8, 13, and 16) is a cam follower in the form of a roller 127 in position of the line of movement of a cam to raise the entire post 121 (Fig. 13) and the attached lock 115, head 103, and finishing tool 100 vertically when the cycle of operations has reached the point for releasing the burnishing tools from contact with the top lift, as will be described.

To effect the angular adjustment of the head 103 along arc-shaped guide and slideways 110 and 112, I secure to the post 121 a stud 130 on which is a bell crank lever 131, best seen in Fig. 13, having one arm 133 mounted under a flat portion of the head 103 and with the opposite arm 134 in contact with a disc 135 secured to the end of a hollow shaft 136 encircling the rod 84 and extending rearwardly or to the left, viewing Figs. 1 and 13, where a yoke 138 is attached thereto, in which a pair of depending pins 139—139 carrying rollers 140 engage the groove in the yoke 138, said pins being mounted in the opposite arms of a shifting lever 141, which lever, see Fig. 2, is pivoted at 144 on a part of the bracket 87 and carries a handle 145 with which to operate the shifting fork. Manipulation of the lever will thus move the shaft 136 to and fro and, consequently, moves the disc 135 and oscillates the bell crank lever to adjust the head 103 angularly with relation to the top-lift on which the tool 100 is working, or to work, and this can be done during the continuous operation of the machine.

The shaft 136 is rotatably mounted within a hollow rock shaft or sleeve 150 which, in turn, is adapted to rock or turn in ball-bearing raceways 151 and 152 arranged in portions 153 and 154 of the frame, and carries at the forward end by a wedging fit the hub 155 of the oscillating box 156 to which the face plate carrying the block 115 and attached parts is secured. Oscillation of the sleeve 150 thus oscillates the box 156 and the tool 100 thru the construction and arrangement of parts thus described. To oscillate these members (Figs. 5 and 11), I secure to the sleeve 150 by a key or wedging fit a pinion 160, preferably adjacent and outside the ball-bearing raceway 151, which pinion is engaged by a rack 161 on a segment 162 mounted to rotate on a stud 163 fitted in the extension on the frame 6.

To oscillate the segment 162 (Fig. 5), I provide a link 165 having its upper end engage a pin 166 on the segment 162 and with its lowermost end bored to receive the shank of a hand wheel 168, said shank having a reduced portion threaded into a tapped recess in a block 170 adapted to slide adjustably in the cross-head 171 and arranged for sliding adjustment in said cross-head by a knurled thumb nut 172, having its shank 173 threaded into a tapped recess in the block 170. Manipulation of the thumb nut 172 produces a shifting of the block 170 and,

hence, a variation in the throw of the link 165 on the segment 162 and, consequently affords an adjustment for the oscillation of the tool 100 on the top-lift being operated on.

The cross-head 171 is attached to the shaft 18, which in turn is rotated when the gear 16 is clutched to the shaft to start the mechanism.

In order to exert a yielding tension upon the tool 100, and in order also to provide means permitting a variation or adjustment of this tension as desired, and at any time during the operation of the machine, I provide novel means to accomplish this desirable result. As best shown in Fig. 14, I form on the post 121 a stud 190, which stud is engaged by a corresponding recess thru one end of the lever 191, having its opposite end mounted on a post 192 fitted within the face plate 90. This lever 191 is formed with a depending web 193, with a bored bearing to receive the end of a rotatable worm 194, the other end of said worm passing thru a corresponding bored opening in the lever 191 adjacent the end surrounding the post 192, and is provided with a miter gear 195 (Figs. 14 and 17) on its outer end, which in turn meshes with the gear 196 secured on a post 197, to which also is attached a knurled adjusting wheel 198, having one portion of said wheel projecting thru a slot 199 in the top of the oscillating box 156, as best shown in Figs. 2 and 17. Attached to the worm 194 is a spring 200, the end of the spring entering the groove in said worm and with the opposite end of the spring attached to a post 201 fitted in the box 156. Thus, by manipulation of the projecting edge of the wheel 198, the worm 194 is rotated and the end of the spring 200 encircling said worm is adjusted lengthwise of the lever 191 to vary the tension desired on the tool 100 and all over the outside of the oscillating box, and at any time.

In order to supply electric current to the heater 106, I attached to the exterior of the oscillating box 156 a pair of metal contacts 204 and 205 mounted upon insulating material 206, said contacts and the insulation being in the form of an arc or crescent to correspond with the oscillations accorded to the box 156, as shown in Figs. 6, 7, and 8, the contact points 207 and 208 being in fixed relation to transferring current to the strips 204 and 205 during the oscillations and, hence, to the heating unit 106, the heating wires being laid therein from any suitable source of power and, preferably, thru a rheostat (not shown) to vary the degrees of heat desired for the particular work in hand.

The heel breast finishing tool 101 is not required to have as great a range of oscillations as that desirable and necessary for the tool 100, since the heel breast of the top lift is relatively short. In order to operate the tool 101 thru the oscillations to-and-fro across the heel breast, and also to move the tool 101 away from contact with the top lift when the two tools are separated to remove a finished heel and replace the same with an unfinished heel, as well also to provide an angular adjustment to the tool 101 to fit varying angular heel breast edges, I mount the tool 101 in a movable holder 210 secured on a support 212 (see Figs. 10, 11, 12, and 13).

To permit the tool 101 to be angularly positioned in its holder 210 I provide on said holder (see Fig. 4) a circularly curved face 228 seating on a correspondingly curved face of holder support 212, the center of curvature corresponding to the edge of the top lift at the breast surface 75

of the heel. To effect angular positioning the holder 210 (see Figs. 10 and 12) carries an arm or lever 230 for manipulating the same and is held in its carrier under yielding tension by spring clip 231 secured to the opposite side of the support by the screw 232.

The support 212 for the breast iron 101 is rigidly attached to a supporting member 214 by screws 215 and has a depending shank 216 adjustably received in a clamp 218 pivotally supported on center 245 at the end of arm 244 of a bell crank lever pivoted on the fixed center 247. The other arm 246 of the lever has a cam follower 248 cooperating with cam 250, which thus serves to position the iron and its support at a variable distance from the heel, viewing, for example, Fig. 10. To maintain the follower in contact with the cam and also to provide an operating pressure of the iron on the heel breast during the burnishing operation, the end of the lever 244 (see Figs. 11 and 18) receives the rounded head 241 of a screw 239 adjustable by means of the knurled head 240, which screw enters the block or nut 238 slidable in casing 234 and is pressed upwardly, viewing the figures, by the spring 233. The casing 234, as seen in Fig. 11, is mounted by a bracket 235 attached to the plate 38 by a bolt 236.

To oscillate the tool 101 the clamp 218 has projecting therefrom the arm 220 to which is connected at 222 the link 221, the other end of which is connected to the oscillating arm 225 by wrist pin 224 adjustable in slot 226. The arm 225 is mounted on the stud 163 and is secured to the segment 162 to move therewith but extends in the opposite direction to the latter. At any given time the pivotal connection of the clamp 218 on the end of arm 220 may be considered as fixed since it is supported relative to the fixed center 247 by the cooperation of the supporting spring 233 on the one hand and on the other the resistance to the thrust of the spring either of the heel in contact with the iron or of the surface of the cam underriding follower 248, as the case may be. Thus, oscillating arm 225, connecting link 221 and arm 220 function as a linkage of the kind known as a double rocking lever, and as the arm 225 oscillates, the arm 220 and the clamp 218 carried thereby will be rocked about the pivotal connection of the latter at 243 to the end of the lever 244 and the iron 101 thus oscillated across the breast surface of the heel.

When the follower 248 is opposite the low portion of the cam 250, the spring 233 acts to press the iron 101 with yielding pressure against the breast surface of the heel, as shown in Figs. 11 and 12. When, however, the follower rides on to the rise portion of the cam, the levers 244-246 swing counterclockwise about the center 247, retracting clamp 218 (and the iron holder and iron carried thereby) downwardly, viewing those figures, against the stress of spring 233 to the position shown in Fig. 10 wherein the iron 101 is away from the heel although it may still oscillate under the action of crank 225 since the pivotal point of connection 245 of the clamp 218 thereto, although shifted, may still be considered a fixed point as regards the operation of the linkage of which the oscillating arm 225 forms a part. This retraction of the breast iron is timed to occur when the iron 100 is retracted, and while the two irons are so retracted, the clamping mechanism for the heel is opened to permit a new heel to be inserted.

Heat is supplied to the tool 101 by a heating

unit 255 held in contact with the support 212 and holder 210 by a spring clip 256 to which heating wires 257 are led from a suitable source of power. The oscillations of the tool 101 and its supporting members are comparatively slight; hence the wires will not be bent. In the heating supply thru the contacts 204 and 205 to the heating element 106 in the oscillating head, a pair of contacts 258—258 are fixed inside the oscillating box 156, and electrically connected to the arc-shaped contacts 204 and 205 on the exterior of the same and from these interior contacts, wires 259 lead to the heating unit 106, see Fig. 14.

Since the heating wires 257 partake of the oscillations of the supporting members for the tools 101, it is desirable to arrange contact plates and brush members therefor, and for this purpose I lead the wires 257 to contact plates 310 and 311 engaged, respectively, by brush contacts 312 and 313 (Fig. 1) which project from a box 315 fixed on an arm of the frame and from which box the heating wires are led to any source of power. This arrangement permits the oscillations of the tool-carrying members supplying current to the heater 255 in a similar manner to that already described with the heating element 106 for the heating tool 100.

The means for releasing the clamping members on the heel 50 will now be described. The cam shaft 260 (Fig. 2) is fitted at one side of the machine in suitable bearings in the frames 5 and 6, and this shaft is rotated by the pinion 261 on the shaft 18 meshing with the gear 262. On the outer end of the cam shaft 260 beyond the frame 5 is a face cam 263 (see Figs. 2 and 9). Mounted on a bracket 264 at one side of the frame 5 on a pivot 265 is a rocker arm 266, having at one end a roll 267 adapted to traverse the cam path 263, the other end of the arm being forked, as shown at 268, Fig. 9, and each fork carrying a pin 269 to engage a groove in the collar 270 secured to the sleeve 47 (Fig. 13). A spring 271 attached to the arm 266 at one end and to the opposite end 272 on a portion of the bracket 273 carrying the bearing 46 holds the rocker arm 266 with its roller in contact with the cam 263.

The actuation of this cam will move the entire heel-clamping mechanism together with the heel-breast rest 17 to the right, viewing Figs. 1, 2, and 13, thus releasing the heel.

The arrangement for raising and lowering the heel breast tool 101 has already been described, and the means for raising the post 121 and, hence, lifting the tool 100 simultaneously to release the heel 50 will now be described. Secured to the pivot pin 275 carried by an arm 276, secured by a bolt 277 to the frame 7, is a link 278 carrying a roll 279 on its side in line to be engaged by a cam 280, see Figs. 5 and 11. At the upper part of the link 278 on a pivot pin 281 is a second link 282 extending across to the opposite side of the machine where it is attached by a pin 283 to an arm 284, carrying a cam 285 on the side, as best shown in Figs. 9 and 11.

This arm 284 is pivoted at 286 to a portion of the frame and is rocked to-and-fro on its pivot 286 by the action of the cam 280 on the roll 279 of the arm 278. After a predetermined number of oscillations of the oscillator 156, the cam 280 rocks the links 278, 282, and 284, to bring the parts into a position wherein they may be effective to retract the iron 100, in the manner now to be described, by action on the projecting cam roller 127 (Figs. 13 and 16) on the post 121, to

which the tool 100 is attached, see Figs. 19 and 20, said roll 127 projecting thru a slot 287 in the rear of the wall of the oscillator 156.

Adjacent this roll 127 is a U-shaped latch 290 pivoted at 291 to the oscillator 156, and having a notch 299 in the upper portion of one arm, viz. the right arm, viewing Figs. 6, 7, and 8. On the left arm 292 is an inclined projection 293 engaged by a trigger 294 held in contact therewith by a spring 295, also secured to the back of the oscillator 156. An upstanding pin 300 is formed on the latch 290 to engage the cam path 285 at a predetermined time, viz. after four complete oscillations of the oscillator 156 and the tools 100 and 101. Formed on the post 123 is a flat surface 301 in line to be engaged by the shouldered portion 299 of the latch 290 when and if the latter is moved underneath the same, as will now be explained.

Referring to the showings in Figs. 6, 7, 8, 19 and 20, the roll 127 on the shaft 123 is engaged by the cam surface 303 on the arm 284 as this arm is moved inwardly or to the left, viewing Figs. 6, 7, 8, 19 and 20, by the links 282 and 278 and cam 280, whereupon the roll 127 in its next oscillation striking against the cam face 303 will be forced radially inwardly along the slot 287, raising the post 121 and oscillated parts and lifting the tool 100 from the top-lift. As the roll 127 nears the end of the slot 287, the spring 295 pressing on the trigger 294 moves the entire latch 290 on its pivot 291 to the left (as shown in Figs. 7 and 19), permitting the notch 299 to be forced under the shaft 123 and the flat surface 301, as shown in Fig. 7, thus holding the tool 100 in raised position until the latch 290 is released.

This release is effected by the pin 300 and a further movement of the arm 284 caused by the raised portion 305 on the cam 280 (Figs. 11 and 20), swinging the cam surface 303 sufficiently inwardly to strike the roll 127 and forcing the same slightly further in the slot 287, lifting the entire attached portion and permitting the trigger 294 to be freed from the engagement of the notch 299 and the surface 301, and substantially simultaneously the cam 285 will be engaged by the pin 300, rocking the latch 290 on its pivot against the tension of the spring 295, which thus will enable the trigger 294 to be snapped around the projection 293 and the trigger is then in the position shown in Figs. 8 and 20, whereupon the roller 127 being released, the action of the spring 200 will serve to move the entire mechanism supporting the tool 100 downwardly in the guideway 126 and return the roll 127 to the outer limit of the slot 287.

Meanwhile, the operator has placed another heel in position and the finishing tools 100 and 101 coming in contact with the top-lift, still under the influence of the respective springs 200 and 233, maintain the yielding tension of the edging or finishing tools in contact with the top-lift during the succeeding oscillations and the burnishing actions.

Referring to Figs. 1, 2, 13 and 15, the irons 100 and 101 (Fig. 13) are of conventional form having flanges overlying the tread face of the lift 80. To permit the operation of both these irons to act on the complete periphery of the heel work rest 81 of the left-hand member of the jack, viewing Fig. 13, is such as to be received entirely within the periphery of the tread so that the flanges may clear the same. It will be noted further that the shaft 84 which carries this work rest is supported at the left-hand side,

viewing Fig. 13, from the supports 153 and 154 and extends therefrom in overhanging relation, passing through the open center of the tool-holding member which carries iron 100, that is, through the hollow shaft 150, the hollow hub 155 which surrounds it, and the hereinbefore described opening formed through the central hub-like portion 88 of the face plate 80. The box 156 which carries this face plate is mounted on the end of shaft 150 and therefore is likewise supported from 153 and 154 in overhanging relation while the iron 100 carried thereby projects at the opposite side so that the supporting means for the iron is organized in an annular zone about the axis of the shaft 84 and no part of the supporting means projects into the plane of the lift within the orbit of the iron 100 to obstruct access of the irons 100 and 101 thereto. Iron 101 (see Fig. 10) is supported and operated by means organized radially outward from the heel lift. The heel seat clamping element 55 of the jack and the breast gauge 77 are likewise supported from the fixed hubs 42 and 46 at the right-hand side of the location of the top lift, viewing Fig. 13, so that again no obstruction is offered to the two irons in their plane of action, that is, in the plane of the top lift, but on the contrary there exists an unobstructed clearance around the top lift when the latter is held by the jack which permits the operation of the burnishing irons on the entire periphery of the heel surface in the same operation, that is, in the case of a heel of conventional form both on the breast and around the outer periphery. In other words, the means for supporting the heel and supporting the irons are organized respectively axially outwardly of the lift and radially outward of the operating paths of the burnishing irons.

I prefer to arrange the cams to permit a series of four oscillations to-and-fro of the burnishing tools on the top-lift, and thereupon the cam 280 will operate as just described.

The operation of the machine will be readily understood. With power applied, the mechanism is constructed and arranged so that the tool 100 and its carrier, and the heel-breast tool 101 and its carrier, will be in continual oscillating motion, and is adapted to make four burnishing operations on the top lift 80 with the tools in contact therewith. Thereupon, the carrier for the tool 100 is lifted and the latch mechanism illustrated in Figs. 6, 7, 8, 19 and 20 is operated to hold the carrier for the tool 100 in raised position while the clamping plate 51 is moved outwardly or to the right, viewed in Fig. 13; thereby releasing the heel 50, which heel is thereupon lifted and removed by the operator, who replaces a new heel on the rest 77 while the oscillations of the tool 100 and 101 still continue but without the burnishing effect. Thus the tool 100 is held in raised position during a complete oscillation by the latch mechanism operated by the cams 280 and 305 and associated parts, which thereupon release the carrier of the top tool 100 to bring the top tool 100 in contact with the top lift 80 just after the clamping plate 51 has been moved to the left to hold the heel 50 in clamped position until an additional cycle of operations, viz., four, are performed by the burnishing tools; whereupon the tool 100 and the clamping plate are again moved to release the heel for removal and replacement of a new heel. The time of one oscillation when the heel is released is ample for the operator to remove the heel with the burnished top lift, and replace with

another heel and top lift to be operated on. Thereupon the operations automatically continue.

I claim:

5. In a machine of the class described a pair of aligned members for contact with tread and seat surfaces of a heel, relatively movable to clamp and suspend a heel between them, edge burnishing means disposed substantially in the plane of the top lift of a heel so held and driving means for effecting relative movement between the clamped heel and said burnishing means causing the latter to traverse substantially in such plane the entire periphery of such top lift.
10. 2. In a machine of the class described a tool carrier having an open center and means exterior to said center for supporting the same, a burnishing iron carried by the carrier facing inwardly toward said center, means for supporting a heel with the periphery of its top lift presented to the burnishing iron comprising opposed elements spaced along an axial line passing through said center and including an overhanging element passing through said open center, said elements and their supports lying in all positions of the elements axially outward of such lift or radially outward of the burnishing iron, whereby the path of the iron is unobstructed thereby throughout the periphery of the heel, and means organized exteriorly of the said path for effecting relative rotation between the tool carrier and the heel supporting means.
15. 3. In a machine of the class described a hollow shaft having a tool carrier at an end thereof, a burnishing iron on the carrier at the side away from said shaft end and facing inwardly toward the axis of the shaft, a rod extending through the hollow shaft having at its extremity a heel engaging element, an opposed heel engaging element, one of the elements engaging the tread of the heel entirely inward of the periphery thereof and the other engaging the heel remote from the top lift whereby the heel is supported with an unobstructed clearance entirely about the same in the path of the iron and means for relatively revolving the tool carrier and said heel engaging elements to cause the iron to travel about the periphery of the heel top lift.
20. 4. A machine of the class described comprising a fixed support having mounted thereon in overhung relation a member for contacting the tread surface of a heel, said member arranged to be received entirely within the periphery of said tread surface, a second fixed support at the side of the heel further from the first support having a member to engage the seat surface of the heel, the members being arranged for relative approach and recession along a line substantially perpendicular to the tread to clamp and release a heel, an iron opposing the periphery of the heel adjacent the tread, means for supporting the same organized in an annular zone about said line, and means for effecting an oscillating rotary movement between a clamped heel and the iron to cause the iron to traverse said periphery, the above described arrangement of the supports and the members carried thereby defining an unobstructed clearance space extending completely around the tread periphery of the heel in the path of the iron.
25. 5. A machine of the class described comprising a fixed support having mounted thereon in overhung relation a shaft having at its extremity a member for contacting the tread surface of

a heel, said member arranged to be received entirely within the periphery of said tread surface, a second fixed support at the side of the heel further from the first support having a member to engage the seat surface of the heel, the members being arranged for relative approach and recession along a line substantially perpendicular to the tread to clamp and release a heel, a rotatable tool-holding member organized about said shaft at a point between said supports carrying an iron opposing the periphery of the heel adjacent the tread, means to impart an oscillating rotary movement to said tool-holding member to cause the iron to traverse the heel periphery, the above described arrangement of the supports and the members carried thereby defining an unobstructed clearance space extending completely around the tread periphery of the heel in the path of the iron.

6. In a machine for finishing the edge portions of top lifts of heels for boots and shoes, comprising means to engage and hold the heel, operating means to engage the top lift edge at a plurality of points, and means to effect relative movement between said top lift and the operating means to operate upon the heel breast and the rear edge portion simultaneously.

7. In a machine for finishing the edge portions of top lifts of heels for boots and shoes, comprising a plurality of finishing tools arranged to contact said edge portion under yielding tension, and means to produce relative rotative movement between the top lift and said tools to finish the entire periphery of the top lift.

8. In a machine for finishing the edge portions of top lifts of heels for boots and shoes, comprising a plurality of finishing tools arranged to contact said edge portion under yielding tension, and means to produce relative rotative movement between the top lift and said tools to automatically finish the entire periphery of the top lift.

9. In a machine for finishing the edge portions of top lifts of heels for boots and shoes, comprising a plurality of finishing tools arranged to contact said edge portion under yielding tension, and means to produce relative rotative movement between the top lift and said tools to automatically finish the entire periphery of the top lift by a plurality of said relative movements.

10. In a machine for finishing the edge portions of top lifts of heels for boots and shoes, comprising a plurality of finishing tools arranged to contact said edge portion under yielding tension, means to produce relative rotative movement between the top lift and said tools to finish the entire periphery of the top lift, and means to adjust the relative angle of said finishing tools and said top lift edge.

11. In a machine for finishing the edge portions of top lifts of heels for boots and shoes, comprising a plurality of finishing tools arranged to contact said edge portion under yielding tension, means to produce relative rotative movement between the top lift and said tools to finish the entire periphery of the top lift, and means to adjust the relative pressure of the edge finishing tools.

12. In a machine for operating upon the top lifts of boot and shoe heels, comprising clamping means to hold said heel and top lift, edge-finishing means adapted to contact with the edge portion of said top lift, means for effecting relative movement between the heel and the edge-

finishing means, said edge-finishing means operating on the heel breast and the remainder of the top lift as a simultaneous operation.

13. In a machine of the class described, means for supporting a heel positioned on an axis extending substantially perpendicular to the tread surface thereof, a setting iron opposing the edge of the heel and means for oscillating it about said axis, a setting iron opposing the breast of the heel and means for oscillating it about a center remote from said axis, and means for moving said irons away from the heel.

14. In a machine of the class described, means for supporting a heel positioned on an axis extending substantially perpendicular to the tread surface thereof, a setting iron opposing the edge of the heel and means for oscillating it about said axis, a setting iron opposing the breast of the heel and means for oscillating it about a center remote from said axis, and means for periodically moving the irons away from the heel without interruption of the action of such oscillating means.

15. In a machine of the class described, a jack having opposed jaws for clamping a heel positioned on an axis extending substantially perpendicular to the tread surface thereof, a setting iron opposing the edge of the heel and means for oscillating it about said axis, a setting iron opposing the breast of the heel and means for oscillating it about a centre remote from said axis, means for moving the irons away from the heel without interruption of the action of such oscillating means, and means for separating the jaws of the jack to release the heel upon such movement of the iron.

16. In a machine of the class described, a jack having opposed jaws, for clamping a heel, an iron carrier mounted for in-and-out movement toward the heel, power means for oscillating the carrier continuously orbitally around the heel, power means for periodically retracting the iron carrier from the heel without interrupting the oscillation thereof, and power means for separating the jaws of the jack to release the heel, such means being timed for operation when the iron carrier is retracted.

17. In a machine of the class described, an iron, means for orbitally oscillating it about an axis, a heel-holder including a part adapted to be advanced substantially along said axis to present the tread portion of the heel to the iron, means for periodically retracting the iron from said axis, and means correlated therewith for thereupon retracting said holder part.

18. In a machine of the class described, an iron, means for orbitally oscillating it about an axis, a heel-holder including a part adapted to be advanced substantially along said axis to present the tread portion of the heel to the iron, means for periodically retracting the iron from said axis without interrupting the oscillation thereof, and means correlated therewith for thereupon retracting said holder part.

19. In a machine of the class described, in combination with means for positioning a heel with its tread surface substantially perpendicular to the axis of the shaft hereinafter referred to, a rock shaft having a tool-holding member projecting outwardly therefrom in a plane transverse thereto, a slide on the member having provision for supporting an iron in over-hanging relation to the shoe heel, an arm pivoted on the member engaging the slide, a spring connected to the arm to press the slide to move the tool

carried thereby inwardly toward the heel, and a follower on the slide projecting from the member and providing means by which the slide may be retracted outwardly against the spring.

20. In a machine of the class described, in combination with means for positioning a heel with its tread surface substantially perpendicular to the axis of the shaft hereinafter referred to, a rock shaft having a tool-holding member projecting outwardly therefrom in a plane transverse thereto, a slide on the member having provision for supporting an iron in overhanging relation to the shoe heel, an arm pivoted on the member engaging the slide, a spring connected to the arm to press the slide to move the tool carried thereby inwardly toward the heel, means accessible at the exterior of the member for shifting the point of attachment of the spring to the arm, and a follower on the slide projecting from the member and providing means by which the slide may be retracted outwardly against the spring.

21. In a machine of the class described, in combination with means for positioning a heel with its tread surface substantially perpendicular to the axis of the shaft hereinafter referred to, a rock shaft having a tool-holding member projecting outwardly therefrom in a plane transverse thereto, a slide on the member having provision for supporting an iron in overhanging relation to the shoe heel, an arm pivoted on the member engaging the slide, a screw extending along the arm, a spring anchored to the member and having a loop engaging the thread of the screw, means accessible at the exterior of the head for turning the screw, and a follower on the slide projecting from the member and providing means by which the slide may be retracted outwardly against the spring.

22. In a machine of the class described, a jack having relatively movable jaws adapted to cooperate respectively with the tread and seat portion of a heel to position it along an axis extending substantially perpendicular to the tread thereof, a rock shaft oscillating about said axis having a tool-holding member projecting outwardly therefrom in a plane transverse thereto, an iron-carrying member thereon movable thereon toward and from said axis and having a projecting cam follower, a cam surface for cooperation with the follower, and means for periodically advancing it into the oscillating path of the follower thereby to move said member away from the axis.

23. In a machine of the class described, a jack having relatively movable jaws adapted to be moved together to engage respectively with the tread and seat portion of a heel to clamp the heel and to position it along an axis extending substantially perpendicular to the tread thereof, a rock shaft oscillating about said axis having a tool-holding member projecting outwardly therefrom in a plane transverse thereto, an iron-carrying member thereon movable thereon toward and from said axis and having a projecting cam follower, a cam surface for cooperation with the follower, and means for periodically advancing it into the oscillating path of the follower thereby to move said iron-carrying member away from the axis, and means coordinated therewith for substantially simultaneous action for axially separating the jaws to release the heel.

24. In a machine of the class described, a jack

having relatively movable jaws adapted to cooperate respectively with the tread and seat portion of a heel to position it along an axis extending substantially perpendicular to the tread thereof, a rock shaft oscillating about said axis having a tool-holding member projecting outwardly therefrom in a plane transverse thereto, a radial slide on the tool-holding member, an iron holder pivotally associated with the slide and having a tail portion adjacent thereto, a rotary member on the slide cooperating with said tail portion to effect pivotal movement of the holder, said rotary member being provided with an arm, and a plunger for contacting said arm extending thru the rock shaft, and operable from the remote end thereof.

25. In a machine of the class described, a jack having relatively movable jaws adapted to cooperate respectively with the tread and seat portion of a heel to position it along an axis extending substantially perpendicular to the tread thereof, a rock shaft oscillating about said axis having a tool-holding member projecting outwardly therefrom in a plane transverse thereto, a radial slide thereon, an iron holder pivotally associated with the slide, a member coaxial with the rock shaft, and having a manipulating portion at an end of the shaft providing for axial movement thereof, and means on the tool-holding member responsive to the pressure of said member for rocking the iron holder without interruption of the oscillating movement thereof.

26. In a machine of the class described, means for supporting a heel along an axis extending substantially perpendicular to the tread thereof, a rock shaft oscillating about said axis having a tool-supporting member projecting outwardly therefrom in a plane transverse thereto, a member carried thereby having provision for supporting an iron in overhanging relation, said iron-supporting member being movable toward and from the axis and normally spring-pressed to move the iron toward the said axis, a cam follower on said member, a latch for securing the iron-supporting member in position with the iron relatively removed from the axis, movable cam surfaces respectively formed to cooperate with the follower to cause outward movement of the iron and to control the latch, and means for moving the cam surfaces into operative position adjacent the tool-holding member to engage the follower and operate the latch respectively.

27. In a machine for setting the edge of a top-lift attached to a heel, a pair of edge-setting irons adapted to engage said lift simultaneously, one arranged to move along the edge of the breast of the top-lift and the other arranged to engage along the remaining edge of the top-lift, and means for causing relative movement of said irons in timed relation so that they are positioned at the extremities of their paths of travel at different times.

28. In a machine for setting the edge of a top-lift attached to a heel, means for holding a heel, edge-setting means including a pair of edge-setting irons one adapted to set the edge of the breast of the top lift and the other adapted to set the edge of the remaining portion of the top-lift, and means for relatively moving said holding means and edge-setting means to cause the latter to set the entire edge of the top-lift.

OSCAR L. LAWSON.
